MOTION PICTURE FILM VIEWER

Tadashi Kuwabara, Kanagawa-ken, Japan. (16 Muro-machi I-chome Nihombashi, Chuo-ku, Tokyo, Japan)

Filed Jan. 7, 1960, Ser. No. 58,958

Term of patent 14 years

(Cl. D61—1)

FIG. 1.

FIG. 2.

FIG. 3.

FIG. 4

FIG. 5.

FIG. 6.

Fig. 1 is a side elevational view of a motion picture film viewer showing my new design;

Fig. 2 is another side elevational view;

Fig. 3 is a rear elevational view;

Fig. 4 is a bottom plan view;

Fig. 5 is a front elevational view thereof with film reels, film and supporting brackets being shown for illustrative purposes only; and

Fig. 6 is a top plan view of the article as shown in Fig. 5.

The dominant features of my design reside in the portion shown in full lines.

I claim:

The ornamental design for a motion picture film viewer, as shown and described.
